CLAIM

What is claimed is the ornamental design for a fan guard, as shown and described.

DESCRIPTION

FIG. 1 is a front-side perspective view of a fan guard showing my new design;

FIG. 2 is a rear-side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depicting the remainder of the fan guard show features that form no part of the claimed design.
